231,717

COMBINED HEEL AND SOLE FOR FOOTWEAR

William Gottlieb, Davenport, Iowa, assignor to Chromally American Corporation, St. Louis, Mo.

Filed Sept. 14, 1972, Ser. No. 290,181

Term of patent 14 years

Int. Cl. D2—04

U.S. Cl. D2—320

FIG. 1 is a bottom plan view of a combined heel and sole for footwear showing my new design; and

FIG. 2 is a sectional view taken on line 2—2 of FIG. 1.

I claim:

The ornamental design for a combined heel and sole for footwear, substantially as shown.
